US0D1032587S

(12) **United States Design Patent** (10) **Patent No.:** **US D1,032,587 S**
(45) **Date of Patent:** **** Jun. 25, 2024**

(54) **CASE FOR ELECTRONIC COMMUNICATION DEVICE**

(71) Applicant: **SHENZHEN GUANGYIPENG TECHNOLOGY CO., LTD.**, Shenzhen (CN)

(72) Inventor: **Jie Weng**, Shenzhen (CN)

(73) Assignee: **Shenzhen Quangyipeng Technology Co., Ltd.**, Shenzhen (CN)

(**) Term: **15 Years**

(21) Appl. No.: **29/852,012**

(22) Filed: **Sep. 2, 2022**

(51) LOC (14) Cl. **03-01**

(52) U.S. Cl.

USPC **D14/250**

CLAIM

The ornamental design for a case for electronic communication device, as shown and described.

DESCRIPTION

FIG. 1 is a front, right, and top perspective view of a case for electronic communication device showing my new design;

FIG. 2 is a rear, left, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a second rear, left, and bottom perspective view thereof, shown in an alternate configuration;

FIG. 10 is an exploded front, right, and top perspective view thereof;

FIG. 11 is a second front, right, and top perspective view thereof, shown with unclaimed environment; and,

FIG. 12 is a third rear, left, and bottom perspective view thereof, shown with unclaimed environment.

The das-dash broken lines in the drawings represent portions of the case for electronic communication device or environmental subject matter that form no part of the claimed design.

1 Claim, 12 Drawing Sheets
